UNITED STATES PATENT OFFICE.

THOMAS WILLARD, OF SAN BRUNO, CALIFORNIA.

ELECTRODE-HOLDER.

1,348,530.

Specification of Letters Patent. Patented Aug. 3, 1920.

Application filed July 25, 1919. Serial No. 313,929.

To all whom it may concern:

Be it known that I, THOMAS WILLARD, a citizen of the United States, residing in the city of San Bruno, in the county of San Mateo and State of California, have invented 5 a new and useful Improvement in Electrode-Holders, of which the following is a specification.

My invention relates to improvements in 10 holders for electrodes used in electric welding wherein an insulated member operates in conjunction with a longitudinally movable metallic head to engage and retain an electrode.

15 The primary object of the present invention is to provide a new and improved holder for welding electrodes.

It is also an object of the present invention to provide a new and improved 20 electrode holder of the character described having means for moving a member longitudinally to clamp an electrode between two metallic members.

A still further object of the invention is 25 to provide insulated members for holding and operating the movable part of said holder thereby reducing to a minimum the possibility and danger of contact of the operator with the metallic portions of the holder.

I accomplish these and other objects by 30 means of the improved device disclosed in the drawings forming a part of the present specification, wherein like characters of reference are used to designate similar parts throughout the said specification and drawings, and in which—

Figure 1 is an elevation of my improved 35 device;

Fig. 2 is a vertical longitudinal sectional view thereof;

Fig. 3 is a broken elevation of one end of 40 the device disclosing the manner in which an electrode is clamped in position; and

Fig. 4 is a plan view of Fig. 3.

Referring to the drawings, the numeral 1 is used to designate an insulated member, preferably cylindrical in shape, provided 45 with a central longitudinal bore 2 and a metallic cap 3 on one end thereof.

A rod 4 having a threaded portion 6 is 50 slidably mounted within the central bore 2 of the member 1 and is provided with a suitable key 7 which engages the metallic cap 3 to prevent rotation of said rod 4 relatively

to the cap 3 and member 1. The rod 4 is also provided at one end thereof with a metallic head 8 equal in diameter to the diameter of the cap 3. The other end of the rod is provided with a suitable socket 9 to engage 60 the end of a suitable metallic conductor 11.

An insulated handle 12 is provided with a tubular extension 14 having a central bore 15 and extending within the central bore 2 of the member 1. The extension 14 is provided 65 with a threaded sleeve 16 which engages the threaded portion 6 of the rod 4.

The handle 12 is rotatably mounted within or connected to the member 1 by means of ferrules 17 and 18 mounted upon the handle 70 12 and member 1, respectively, and provided with inwardly turned annular flanges which are rotatably engaged by an outwardly faced annular channel 19 whereby said handle 12 may rotate relatively to the member 1. 75

The bore 15 of the handle 12 is provided with an enlarged portion 21 within which the socket 9 of the rod 4 may move longitudinally.

In operation the conductor 11 is connected 80 to the rod 4 by means of the socket 9. The handle 12 is rotated relatively to the member 1 which will cause the threaded sleeve 16, in engaging relation with the threaded 85 portion 6 of the rod 4, to move said rod 4 longitudinally and thereby move the head 8 away from or toward the metallic cap 3 on the ends of the member 1 and thereby release or clamp an electrode 22 between said head 90 3 and the metallic cap 3.

It is obvious that a sufficient contact will 95 thus be provided between the electrode 22 and the holder, as said electrode 22 will be engaged throughout the full diameters of the cap 3 and head 8.

It is also obvious that the handle 12 may be rotated to release or engage the electrode 22 without twisting the conductor 11 as the rod 4 is not rotated with the handle 12 but moved longitudinally within the member 1 by said rotation.

From the foregoing it is evident that I have provided a new and improved electrode holder for electric welding wherein only a small portion of charged metallic surface is exposed to contact with the operator. It is also obvious that said electrode may be easily released without contact with the metallic portions of the holder thereby reduc- 110

ing to a minimum the possibility of contact of the operator with the electrically charged portion of the device.

Having thus described my invention what I claim as new and desire to secure by Letters Patent is—

1. An electrode holder for electric welding comprising an insulated member having a metallic cap on one end thereof; a rod slidably mounted within the member and cap and having a metallic head thereon for engaging an electrode between said cap and head; and an insulated means for moving the rod and head longitudinally within the member to engage and retain an electrode between said head and cap.

2. An electrode holder for electric welding comprising an insulated member having a metallic cap on one end thereof; a threaded metallic rod slidably mounted within said member and cap and having a metallic head on the outer end thereof; means for connecting a metallic conductor to the other end of the rod; and insulated means rotatably mounted upon the insulated member and en-

gaging the threaded portion of the rod whereby rotation of said insulated means will move the rod longitudinally within the insulated member to engage and retain an electrode between the head and metallic cap. 30

3. An electrode holder for electric welding comprising an insulated member having a central bore and a metallic cap on one end thereof; a threaded rod slidably mounted within said central bore and having a metallic head thereon; means for preventing rotation of the rod and head relatively to the cap and insulated holder; and an insulated handle rotatably connected to the insulated member and having a tubular extension extending within the bore of the member and engaging the threaded portion of the rod whereby rotation of said handle will move the rod and head longitudinally within the member to engage and retain an electrode 45 between said head and metallic cap.

In witness whereof I hereunto set my signature.

THOMAS WILLARD.
